US00D803056S

(12) **United States Design Patent** (10) Patent No.: **US D803,056 S**
Pellerin (45) Date of Patent: **** Nov. 21, 2017**

(54) **FLASK WITH CAP**

(71) Applicant: **BERICAP**, Longvic (FR)

(72) Inventor: **Philippe Pellerin**, Dijon (FR)

(73) Assignee: **Bericap**, Longvic (FR)

(**) Term: **15 Years**

(21) Appl. No.: **35/500,321**

(22) Filed: **Jun. 19, 2015**

(80) **Hague Agreement Data**

Int. Filing Date: **Jun. 19, 2015**

Int. Reg. No.: **DM/088288**

Int. Reg. Date: **Jun. 19, 2015**

Int. Reg. Pub. Date: **Dec. 4, 2015**

(30) **Foreign Application Priority Data**

Dec. 19, 2014 (EM) 002602706

(57) **CLAIM**

The ornamental design for a flask with cap, as shown and described.

DESCRIPTION

1. Flask with cap

2. Flask with cap

3. Flask with cap

4. Flask with cap

1.1 : Perspective

1.2 : Front

1.3 : Bottom

1.4 : Top

1.5 : Right

1.6 : Left

1.7 : Back

2.1 : Perspective

2.2 : Front

2.3 : Bottom

2.4 : Top

2.5 : Right

2.6 : Left

2.7 : Back

3.1 : Perspective

3.2 : Front

3.3 : Bottom

3.4 : Top

3.5 : Right

3.6 : Left

3.7 : Back

4.1 : Perspective

4.2 : Front

4.3 : Bottom

4.4 : Top

4.5 : Right

4.6 : Left

4.7 : Back

The broken line showing of the connections of the cap to the flask is for the purpose of illustrating portions of the cap and forms no part of the claimed design.

1 Claim, 28 Drawing Sheets
